CLAIM

The ornamental design for a door panel, as shown and described.

DESCRIPTION

FIG. 1 is a front elevational view of a door panel showing our new design;

FIG. 2 is a front elevational view of a second embodiment of a door panel;

FIG. 3 is a front elevational view of a third embodiment of a door panel;

FIG. 4 is a front elevational view of a fourth embodiment of a door panel;

FIG. 5 is a front elevational view of a fifth embodiment of a door panel;

FIG. 6 is a front elevational view of a sixth embodiment of a door panel;

FIG. 7 is a cross-sectional view of the door panel taken along line 7—7 in FIG. 1;

FIG. 8 is a cross-sectional view of the door panel taken along line 8—8 in FIG. 2;

FIG. 9 is a cross-sectional view of the door panel taken along line 9—9 in FIG. 3;

FIG. 10 is a cross-sectional view of the door panel taken along line 10—10 in FIG. 4;

FIG. 11 is a cross-sectional view of the door panel taken along line 11—11 in FIG. 5;

FIG. 12 is a cross-sectional view of the door panel taken along line 12—12 in FIG. 6; and,

FIG. 13 is an enlarged fragmented perspective view of a groove of the door panel illustrated in FIGS. 1 through 6. This view is broken for convenience of illustration.

The broken lines are for illustrative purposes only and form no part of the claimed design.
